UNITED STATES PATENT OFFICE.

ROBERT FRANCIS CONLON, OF MANCHESTER, ENGLAND.

COCK AND THE LIKE.

1,309,018.

Specification of Letters Patent.

Patented July 8, 1919.

Application filed November 6, 1918. Serial No. 261,406.

To all whom it may concern:

Be it known that I, ROBERT FRANCIS CONLON, a subject of the King of Great Britain and Ireland, and resident of Manchester, England, have invented certain new and useful Improvements in or Relating to Cocks and the like, of which the following is a specification.

This invention relates to cocks and the like of the metal to metal type, primarily intended for the control of petrol and analogous liquids and has for its object to provide an efficient and durable cock of the kind referred to in which the liability to leak is obviated and in which there is no tendency of the working faces to gall or bind in use.

As usually constructed cocks of the kind referred to consist of a gun metal body with the inlet and outlet in one and the same plane, bored out to suit a gun metal tapered plug. The aforesaid body and tapered plug are then ground in by means of an abrasive powder. The tapered plug is retained in position by a spring held in tension by the projection of the smaller end of the tapered plug through the body. With the tapered plug in the "on" position, a hole is drilled at right angles to the aforesaid tapered plug connecting the inlet and outlet of the body.

It is found however, that the efficiency decreases with wear in this type of cock and owing to the frequent presence of impurities in fluids, the operating faces become badly scored and also because of the peculiar properties of petrol and analogous liquids, the movement of the operating faces is extremely harsh.

According to the present invention the tapered plug is lined or covered with a suitable anti-friction white metal or tin during the course of construction and instead of extending beyond the casing is inclosed therein the reduced spindle being elongated to receive a spiral or like spring which at its outer end abuts against a screwed cap on the casing, said spring being in compression and tending to force the plug on to its seat. Suitable inlet and outlets are provided for the liquid and if desired separate inlet and outlets may be provided to control the air supply when the device is used in connection

with the petrol and like tanks wherein the liquid is supplied under pressure.

When it is desired to use the same cock to regulate the supply from or to more than one tank or reservoir the necessary ports or passages are provided and the tap may be used in combination with an indicator to indicate the source of supply or the passages in the cock which are operative.

The invention will be more particularly described by the aid of the accompanying drawings, wherein:

Figure 1 is a part sectional elevation of a petrol cock constructed according to the invention.

Fig. 2 is an end elevation of the same.

Fig. 3 is a detail view of the body part of the plug and

Fig. 4 is a sectional view of the completed plug.

Fig. 5 is a sectional elevation of a three-way cock constructed according to the invention which is also provided with airways.

Fig. 6 is a plan view of Fig. 5.

Fig. 7 is a cross section view of the plug through the liquid passages while

Fig. 8 is a similar view through the air passages.

Fig. 9 is a diagrammatic view showing the cock illustrated in Fig. 5 adapted to control the supply of petrol from two tanks, and

Fig. 10 shows in detail the cock indicator.

Referring to Figs. 1 to 4 the plug *a* comprises a body part, one end *b* of which constitutes the spindle having the squared extremity *c* to receive the manipulating handle *d*, while the other end *e* is cylindrical and has a roughened or fluted outer surface, the flange *f* intervening between the two portions. The portion *e* is tinned and then placed in a mold and a lining or covering of anti-friction white metal, tin or the like is cast around the same.

When set, the lining *g* is machined to form a dead fit for the tapered bore of the casing *h* the extremity of said casing being screwed to receive the cap *i* and recessed to accommodate the compression spring *j* adapted to force the plug on to its seat. The casing *h* is provided with an inlet *k* and outlet *l*, cor-

responding ports being drilled, or otherwise provided in the plug. The cap *i* is locked in position by the grub screw *m* which projects sufficiently far to constitute a stop for the handle *d*.

It is essential that the metal or alloy employed for the aforesaid lining or covering should be of a durable nature and not subject to undue wear, while at the same time being sufficiently ductile to allow hard impurities in the fluid to bed into the lining or covering, rather than score the harder face.

Although an anti-friction white metal has been found most suitable for the aforesaid lining or covering by reason of its freedom from wear, galling or binding, while readily conforming or "bedding in" to the surface or surfaces of the opposing face or faces and at the same time possessing a low coefficient of friction which is of advantage in the actuation of the operating faces any other material possessing these qualities may be used in place of the aforesaid alloy.

When it is desired to use the cock for two or more fluids, or for fluids from different sources of supply, inlet and outlet ports are provided accordingly. In Figs. 5 to 10 an arrangement is shown in which the invention is adapted to control the supply of petrol from two tanks and also the supply of pressure medium to said tanks. In this case the plug *a* and casing are formed and assembled as before described but the casing is provided with a bracket or fitting constituting a screwed stopper *n* for a petrol tank. The plug is provided with two three-way ports *o* and *p* to control petrol and air respectively. The ports *o* are adapted to register with the inlet ports *r* and *s* in the casing which communicate with the main tank *t* and auxiliary tank *u* respectively (see Fig. 9) through the pipes *t'*, *u'*, the outlet *l* communicating, via the pipe *l'* with the engine carbureters as shown. The ports *p* are adapted to place the outlet ports *w* and *x*, leading to the main and auxiliary tanks *t* and *u* respectively, in communication with the air inlet port *v*.

In this case the handle *d* is carried to any convenient position, say the dash-board by means of the spindle *y* connected to the plug spindle by means of the universal joint *z* said handle having a finger *d'* thereon adapted to move over an indicator *d''* whereon the position of the plug ports relative to the casing ports are indicated.

The action of the device will be obvious from the drawings and the respective ports are so arranged that as the petrol outlet ports are in operation for one tank the pressure medium inlet ports for the same tank is operative.

It is of course obvious that the invention can be embodied in greatly modified forms

without departure from its essential features and I wish it to be understood that I in no wise limit the claims to the special construction shown except where such special construction is expressly referred to in the 70 claims.

What I claim is:—

1. In valves, cocks and the like for the control of petrol and analogous liquids comprising a casing and a valve proper, anti-friction white metal lining between the contacting parts which while of a durable nature and not subject to any undue wear is sufficiently ductile as to allow hard impurities in the fluid to bed into the lining or 80 covering rather than score the harder face, substantially as described.

2. Valves, cocks and the like for the control of petrol and analogous liquids comprising a body part, a relatively rotatable plug 85 formed with a tapered conical seating of anti-friction white metal, inlet and outlet ports in the casing and corresponding passages in the plug, a spring interposed between the large end of the plug and an abutment secured to the casing together with means to rotate the plug, substantially as described.

3. Valves, cocks and the like for the control of petrol and analogous liquids comprising a body part, a relatively rotatable plug formed with a tapered conical seating of anti-friction white metal located in said casing, three-way inlet and outlet ports in the casing and corresponding passages in the plug, a cap secured to the casing through which the valve spindle projects and a compression spring located between the tapered plug and the cap adapted to force the plug on to its seat, substantially as described.

4. Valves, cocks and the like for the control of petrol and analogous liquids comprising a body part, a relatively rotatable plug formed with a tapered conical seating of anti-friction white metal located in said casing two or more sets of ports in the casing and plug for controlling two or more fluids, a cap secured to the casing through which the valve spindle projects and a compression spring located between the tapered plug and the cap adapted to force the plug on to its seat, substantially as described.

5. Valves, cocks and the like for the control of petrol and analogous liquids comprising a casing, a relatively rotatable plug 120 formed with a tapered conical seating of anti-friction white metal located in said casing, two or more sets of three-way ports in the casing and plug, a cap secured to the casing through which the plug spindle projects and a compression spring located between the cap and the tapered plug, substantially as described.

6. Valves, cocks and the like for the control of petrol and analogous liquids com-

prising a casing, a relatively rotatable plug formed with a tapered conical seating of anti-friction white metal located in said casing, two or more sets of three-way ports in the casing and plug, a cap secured to the casing through which the plug spindle projects and a compression spring located between the cap and the tapered plug, means to rotate the plug together with means to

indicate the angular position of said plug 10 relatively to the casing, substantially as described.

In witness whereof I have hereunto set my hand in the presence of two witnesses.

ROBERT FRANCIS CONLON.
